CLAIM

The ornamental design for a multi-purpose hand tool, as shown and described.

DESCRIPTION

FIG. 1 is a front elevational view of a multi-purpose hand tool showing my new design; a back elevational view thereof appears as a mirror image of the front elevational view;

FIG. 2 is a left side elevational view thereof;

FIG. 3 is a right side elevational view thereof;

FIG. 4 is a top plan view thereof; and,

FIG. 5 is a bottom plan view thereof.
